TARY ASSOCIATION.

CARTRIDGE-CLIP.

1,202,343.

Specification of Letters Patent. Patented Oct. 24, 1916.

Application filed May 28, 1916. Serial No. 100,019.

To all whom it may concern:

Be it known that we, Joseph H. Wesson and Edward S. Pomeroy, both citizens of the United States of America, and residents of Springfield, in the county of Hampden and State of Massachusetts, have jointly invented certain new and useful Improvements in Cartridge-Clips, of which the following is a specification.

10 This invention relates to cartridge clips or cartridge packs for revolvers. Its object is to provide a simple clip, in one piece of resilient plate metal, having recesses from which confined cartridges or shells cannot escape except by being forcibly removed by a tilting movement.

The preferred construction is shown in the accompanying drawings, wherein—

Figure 1 is a side elevation of a cartridge pack; Fig. 2 is an end elevation thereof, one of the cartridges being removed; Fig. 3 is a face view of the cartridge clip, on an enlarged scale; Fig. 4 is a fragmentary elevation on the same scale as Fig. 3, showing the 25 tilting action required to insert or remove a cartridge or shell; Fig. 5 shows a fragment of Fig. 3, of modified construction.

Referring to the drawings, A is the cartridge clip and B B are the cartridges or cartridge shells, as the case may be. The cartridges shown are of the headless type, the clip engaging the usual V-groove or neck of the cartridge.

The clip A is formed of thin resilient 35 metal plate, as spring steel, being cut or punched out preferably to the form shown in Fig. 3. It has a central opening a to admit the ratchet boss on the cylinder, and has as many cartridge recesses or sockets 40 b, b, as there are chambers in the cylinder, six being shown. These recesses b are not circular so as to closely embrace the circular neck of the cartridge. It will be seen, by comparing the dotted circle c which indicates the size of such neck, with the outline of the recess b in Fig. 3, that each recess is widened at d, e on opposite sides sufficiently to admit the passage through it of the base flange or head of the cartridge when the latter is tilted. The outer side of each recess is closed by a spring finger f which, when a cartridge is in place, may touch the neck of the cartridge or lie close to it. In order

to insert the cartridge it is necessary to present it obliquely to the clip and introduce its base flange obliquely into the widened portions d, e of the recess, which, however, are insufficient in opening to admit the cartridge without a yielding or springing of the finger f; it is necessary, therefore, to bring outward pressure to bear upon this finger, which is easily done by the cartridge itself while obliquely entering it. When the base of the cartridge has thus been entered within the recess and past the finger f, the latter springs back into place and the cartridge, being straightened within the recess, is confined and held therein in its proper position. The cartridges thus entered are somewhat loosely held so as to be brought into approximate, but not necessarily precise, alinement with the chambers in the cylinder.

In case one or two shots are fired and it is then desired to fully re-load the revolver, 75 it is easy to withdraw the pack by the usual ejecting movement and then to remove the spent shells and replace them with new cartridges. Such removal is accomplished by a tilting movement the reverse of that employed in introducing the cartridges.

It is preferable that the irregular shaped openings forming the recesses shall have their greater diameters on the sides approximately toward the center and toward 85 the exterior, the major axis of the openings being in a direction approximating a radial direction; but the recesses may be otherwise shaped and the spring fingers otherwise applied, it being only necessary that 90 the clip shall, by means of spring fingers or other analogous shapings, be provided with recesses of such shape as to loosely confine the necks of the cartridges while, by the yielding of the spring fingers or 95 other portions of the walls of the recesses, to permit the cartridges to be entered or removed by a tilting movement.

Fig. 5 shows a modification wherein the same result is reached by a somewhat different shape of recess, the clip having projections g, g which, co-acting with the end portion h of the spring finger f, form a three-point support for the neck of the cartridge. By exerting outward pressure 105 against the spring finger and then tilting

the cartridge, the latter may be withdrawn, or, by a reverse motion, may be entered into the recess.

It is possible by a further modification of the construction to introduce the cartridge without tilting it, since the finger *f* may be sprung out of the plane of the clip a distance equal to the thickness of the base flange, whereupon, by engaging the neck of the cartridge with the finger and then pressing the latter outwardly or away from the center, the cartridge base may be passed through the thus enlarged recess while the cartridge occupies a position perpendicular to the plane of the clip.

We claim as our invention:—

1. A cartridge clip consisting of a plate of spring metal formed with recesses for receiving the necks of the cartridges, a marginal portion of each recess being resilient and the recess being widened, so that upon springing out said resilient portion the cartridge may be entered or removed from the recess by bringing it into tilted position.
2. A cartridge clip formed of spring plate having cartridge recesses of irregular shape, one side of each recess being formed by a spring finger and the recess being sufficiently wide opposite such finger to permit the passage of the cartridge base by springing the finger, whereby the cartridge may be inserted or removed by a tilting movement.

3. A cartridge clip formed of spring plate having cartridge recesses, one side of each recess being substantially unyielding, and the other side being formed by a spring finger adapted to yield sufficiently to permit the insertion of the base flange of the cartridge within the recess, and normally engaging the neck of the cartridge when the latter is in place.

4. A cartridge clip consisting of a plate of spring metal formed with recesses for receiving the necks of the cartridges, and formed with spring fingers, each finger projecting partly across the open side of one recess, and adapted to yield sufficiently to permit a cartridge to be inserted by a tilting movement.

5. A cartridge clip consisting of a plate of spring metal formed with recesses for receiving the necks of the cartridges, and formed with spring fingers, each finger arranged in circumferential direction with its free end projecting partly across the open side of one recess.

In witness whereof we have hereunto signed our names in the presence of two subscribing witnesses.
